UNITED STATES PATENT OFFICE.

WALTER GUY RICKETTS, OF TULSA, OKLAHOMA, ASSIGNOR OF ONE-FOURTH TO CLYDE E. HOPKINS, OF OKMULGEE, OKLAHOMA, ONE-FOURTH TO ALBERT L. FORQUER, AND ONE-FOURTH TO GEORGE H. MYERS, BOTH OF TULSA, OKLAHOMA.

FLOW BARREL.

Application filed October 21, 1921. Serial No. 509,362.

To all whom it may concern:

Be it known that I, WALTER GUY RICKETTS, a citizen of the United States, and resident of Tulsa, in the county of Tulsa and State of Oklahoma, have invented certain new and useful Improvements in Flow Barrels, of which the following is a specification.

This invention relates to flow barrels especially adapted for use in oil wells.

Briefly stated the improved flow barrel was devised as a means to increase the output from pumping wells and while the improved flow barrel is interposed in the tubing, it is constructed entirely separate from the working barrel. However the improved flow barrel assists the working barrel in that it enables the well to flow as it pumps and in that way releasing the dead weight of the column of oil in the tubing. The flow barrel is intended for use only in wells that produce considerable gas with the oil and is provided with means whereby to relieve the gas pockets in the oil column. It may be placed anywhere in the tubing of the well so long as it is above the working barrel and beneath the level of the oil. In actual practice when a well starts pumping the down stroke of the pumping jack forces the column of oil in the bottom of the tubing up through the working barrel and continues in this manner until the whole tubing of the well is filled with oil and it is forced to the surface into a tank or receptacle provided for the purpose.

In case considerable gas is in the well a vacuum is created in the tubing and any gas and oil that is on the outside of the tubing would seek this vacuum if an opening is created for its entrance. The improved flow barrel is provided with novel means whereby the gas and oil on the outside of the tubing may enter the tubing and thereby relieve the dead weight of the oil and eliminate the gas pockets.

By the use of the improved flow barrel in the tubing, the production is greatly increased and the uniform operation of the well is provided for.

In the accompanying drawing forming a part of this application and in which like numerals are employed to designate like parts throughout the same,

Figure 1 is a fragmentary side elevation of the improved flow barrel.

55

Figure 2 is a group view of a valve embodied in the invention, parts being shown in section.

Figure 3 is a fragmentary side elevation of the improved flow barrel applied, the view being taken at right angles to Figure 1 and parts being shown in section.

Figure 4 is a fragmentary elevation of an inlet pipe of modified construction.

In the drawing wherein for the purpose of illustration is shown the preferred embodiments of the invention, the numerals 5 designate three sections of a string of tubing through which the oil and gas flow. The improved flow barrel consists of upper and lower couplings 6 and 7 respectively which have threaded engagement with the intermediate sections 5 and with the outer sections 5 and which provide a means for connecting the several sections of the tubing illustrated. The lower coupling 7 is provided with a laterally extending shoulder or projection 8 having threaded sockets for the reception of oil and gas inlet pipes 9 of which there are two in this case. The oil and gas inlet pipes 9 may be provided with spaced apertures 10 as illustrated in Figures 1 and 3 or with spaced slots 11 as illustrated in Figure 4.

The upper end of the inlet pipe 9 is provided with threads adapted for engagement with the threads 12 of a valve nut 13, the said valve nut 13 being provided with a seat 14 which coacts with the spherical valve 15. A valve casing 16 of tubular formation has its lower end threaded and adapted for engagement with the interiorly threaded portion 17 of the valve nut 13 and is provided with an inwardly extending shoulder 18 of annular formation for engaging an annular shoulder 19 on the upper portion of the valve nut 13.

The upper portion of the valve casing 16 is interiorly screw threaded as indicated at 20 and is adapted for threaded engagement with the attaching portion 21 of a nipple or short length of pipe 22 having a slotted extension 24 through which the oil passes upon leaving the vertical check valve. With reference to Figure 2 it will be observed that the lower end of the slotted portion 24 is

closed so that the upward movement of the valve 15 will not prevent the movement of the oil through the portion 24.

The upper portion of the nipple 24 is 5 adapted to receive a slip joint nipple 25 having threaded engagement with the bottom wall of a by-pass chamber 26 formed on the coupling 6. The chamber 26 is formed in a laterally extending shoulder in the 10 coupling 6 and the said shoulder is arranged directly above and in alignment with the shoulder 8 so that the several parts of the flow barrel may be readily assembled when desired.

15 In operation the improved flow barrel assists the working barrel in that by its action it enables the oil to flow as pumped and in this way relieving the dead weight of the column of oil in the tubing.

20 Should there be gas pockets in the well the same may be eliminated by placing one or more of the flow barrels in the string of tubing at a point or points where the gas pockets exist and pressure of the gas will 25 elevate the ball valve 15 so that the gas will flow upwardly through the string of tubing.

In actual operation the improved flow barrel greatly increases the production in a well that does not exhaust the oil by 30 pumping 24 hours a day. The parts are interchangeable from one barrel to another of the same size and the improved flow barrel may be used with any pumping barrel now in general use.

35 The average well which produces a considerable amount of gas with the oil in the pumping stage will flow about every half hour due to the gas accumulating sufficient pressure under the constant agitation by 40 pumping to force the whole column of oil, or a part of it up through the tubing. After the flow has taken place, the tubing will again fill with oil until the gas pressure is strong enough to cause another flow and this 45 cycle will be repeated as long as the gas is present in sufficient quantities to exert this action.

When a flow takes place as described above, a vacuum is created in the tubing, 50 causing an unequal pressure to be exerted on the outside of the tubing. The flow barrel being interposed in the lower part of the tubing provides a novel means for equalizing this pressure and for allowing the oil 55 and gas on the outside to pass up through the perforated or slotted pipe up through the ball and the seat check valves into the tubing to fill this vacuum, and when this action is started the well does not repeat 60 the flowing cycles but sprays oil and gas continuously, or at such short intervals as to appear continuous.

The principle upon which the flow barrel 65 operates can be understood best by observing two pumping wells, one of which has the

usual pumping apparatus and the other one equipped with a flow barrel in addition to the pumping parts. On opening the stop at the mouth of the first well, a column of gas will be seen issuing from the small pipe, 70 or a column of gas and oil if the well is making a flow. In the second well this column will consist of both oil and gas in the form of a steady spray coming at such short intervals as to seem continuous. 75

As a result of this continuous flowing action set up in the well the tubing does not fill up with oil as it did and the rods and other pumping equipment are not subjected to an irregular working load, thereby 80 relieving them of a certain portion of this resultant strain which eliminates an appreciable percentage of breakage to rods and the splitting of tubing due to pressure.

In operation the improved flow barrel is 85 interposed in a tubing 10 or 20' above the pumping barrel depending upon the fluid level and other conditions in the well and by allowing the gas to enter the tubing from the casing the movement of the oil up 90 through the well is greatly facilitated. That is to say the admission of the gas into the tubing assists the flowing of the oil up through the tubing without the strain ordinarily present on the working parts of a 95 well as a result of equalizing the pressure on the various parts.

Having thus described the invention, what I claim is:—

1. A flow barrel comprising a coupling 100 adapted to be interposed in a string of tubing, an inlet pipe connected at one end to the coupling and having a plurality of inlet openings to receive the gas and oil exteriorly of the tubing, said coupling being 105 formed with a by-pass establishing communication between the pipe and the string of tubing, whereby the gas and oil exteriorly of the tubing may flow through the pipe into the tubing, and means to firmly attach the other end of the pipe to the tubing and 110 to close the same.

2. The combination with a string of tubing, of couplings interposed therein, an inlet pipe connected to said couplings, and having gas inlet openings and a check valve 115 controlling the flow of gas through said inlet pipe, one of said couplings being provided with a by-pass having communication with said inlet pipe. 120

3. The combination with a string of tubing, of couplings interposed therein, inlet pipes connected to said couplings, and having their lower ends closed and a check valve arranged in said inlet pipes, one of 125 said couplings being provided with a by-pass having communication with said inlet pipes, said inlet pipes being provided with openings through which the fluid passes.

4. The combination with a string of tub- 130

- ing, of upper and lower couplings interposed in said string of tubing, the lower coupling being provided with a laterally extending shoulder having blind sockets, in-
5 let pipes threaded into said sockets and having openings to receive the gas exteriorly of the tubing, valve nuts threaded on said inlet pipes and having valve seats, valves mounted on said seats, valve cages threaded on said nuts, nipples having threaded engagement with said valve cages, and a slip joint coupling connected to the upper coupling.
5. The combination with a string of tubing, of upper and lower couplings interposed in said string of tubing, the lower coupling being provided with a laterally extending shoulder, inlet pipes threaded into said shoulders and closed thereby, said pipes being provided with openings to receive the gas exteriorly of the tubing, valve nuts threaded on said inlet pipes and having valve seats, valves mounted on said seats, valve cages threaded on said nuts, nipples having threaded engagement with said valve cages, a slip joint coupling connected to the upper coupling, said upper coupling being provided with a by-pass in communication with said inlet pipes.
- 10 6. A flow barrel for oil wells comprising couplings adapted to be interposed in a string of tubing, an inlet pipe connected to said couplings and having its lower portion closed by one of said couplings, the other coupling being formed with a by-pass 35 establishing communication between the pipe and the tubing, said pipe being provided with openings whereby the gas exteriorly of the tubing may flow through the pipe and into the tubing.
- 15 7. A flow barrel for oil wells comprising couplings adapted to be interposed in a string of tubing, an inlet pipe connected to said couplings and having its lower portion closed by one of said couplings, the other coupling being formed with a by-pass 40 establishing communication between the pipe and the tubing, said pipe being provided with openings whereby the gas exteriorly of the tubing may flow through the pipe and into the tubing, and a one-way valve interposed in said pipe.
- 20 8. A flow barrel comprising a coupling adapted to be arranged in a string of tubing, an inlet pipe connected at one end to the coupling and having a plurality of inlet openings to receive the gas and oil exteriorly of the tubing, said coupling being formed with a by-pass 45 establishing communication between the pipe and the string of tubing whereby the gas and oil exteriorly of the tubing may flow through the pipe into the tubing, a one-way valve for admitting the gas and oil to said by-pass, and means to attach the other end of the pipe to the tubing and to close the same.
